GAS RANGE CONSTRUCTION

Arthur P. Schulz, Hinsdale, Ill., assignor to G. and
J. Teller, Chicago, Ill., a partnership composed
of Grace Teller and Jacob Teller

Application January 10, 1939, Serial No. 250,234

8 Claims. (Cl. 126—39)

This invention relates to a gas range construction.

One of the many objects of the invention is the provision of a frameless gas range construction which essentially embodies a cooking top unit, a base unit and an oven unit disposed between the cooking top and base units adjacent corresponding ends thereof, the range being completed by opposite end jackets and a front door between the 10 oven unit and the adjacent jacket, thereby providing a range which is light in weight, as well as convenient of operation.

A further object of the invention is the provision of a gas range of the above noted character 15 wherein the cooking top and base units each embody a marginal frame consisting of a seat pre-formed strip and wherein the preformed strips as well as the end jackets and door are provided with attractive contrasting colors in vitreous or 20 synthetic enamel whereby a range of highly attractive appearance is provided.

A still further object of the invention is the provision of a gas range comprising a cooking top having a front stationary working surface and 25 a rear tilt-top section which in one position thereof provides a further working surface in continuation of the stationary surface, and in another selective position thereof provides a cooking top.

30 A still further object of the invention is the provision of a gas range including an oven unit which embodies a box-like portion having a swinging door for normally closing an opening in the front thereof, the door having means for supporting a broiler pan and an oven rack and the box-like portion having a burner supported therein for vertical adjustment between the broiler pan and oven rack.

For a more complete understanding of the 40 nature and objects of the invention, reference will be had to the following detailed description, taken, in connection with the accompanying drawings, wherein:

Fig. 1 is a perspective view of a range constructed in accordance with a preferred embodiment of the invention.

Fig. 2 is a horizontal section through the oven unit substantially in a plane as represented by the broken line 2—2 in Fig. 3, the operating rod 50 and associated pulley being shown above such section.

Fig. 3 is a vertical section of the oven unit in a plane substantially as represented by the line 3—3 in Fig. 2, the broiler pan and oven rack being omitted in this view.

Fig. 4 is an exploded view showing the various cooperating units of the range assembly in perspective and in separated relation, the oven burner adjusting means being slightly modified from that described in Figs. 1, 2 and 3.

Fig. 5 is a perspective view of the oven unit shown in Fig. 4 with the door thereof in open position, exposing the adjustable burner, broiler pan and oven rack.

Fig. 6 is a vertical sectional view of a range 10 of modified construction, and

Fig. 7 is a fragmental view partly in top plan and partly in horizontal section of a friction clutch.

Referring now in detail to the drawings by 15 reference characters, and wherein like characters designate like parts, R designates the range in its entirety.

The range R embodies in its construction a 20 cooking top unit C, a splasher back S for detachable operative associations with the cooking top unit C, a base unit B, an oven or combined oven and broiler unit O, opposite end jacket plates J, and a door D.

The cooking top unit C comprises a marginal frame 10 which is preferably formed by beveling a preformed rolled strip of sheet metal and suitably welding the adjacent ends thereof supported by the frame 10 is a panel 11 having a suitable temperature control 12 mounted therein supported by the frame 10 at the front thereof and extending throughout the length thereof is a fixed working top section 13 and supported by the frame 10 rearwardly of the section 13 is a tilt-top section 14 which is pivotally connected 35 with the frame as indicated at 15.

The tilt-top section 14 embodies a plane surface at one side thereof which in the position shown in Figs. 1 and 4 is co-planular with the fixed section 13 for providing a working surface 40 at the full horizontal area of the frame 10.

The section 14 is selectively rotatable through an arc at 180° from the position indicated to that in which the cooking burners are exposed for use by means of a handle 16.

45 The base unit B embodies a marginal frame 17 similar in construction to the frame 10 and which is supported by suitable ornamental feet 18. Supported by the frame 17 intermediate the opposite ends thereof is an oven unit supporting 50 member 19 and suitably supported by the frame between the member 19 and one of the ends of the frame is a floor 20.

The splasher back S is provided with suitable brackets 21 at opposite ends thereof for detachable 55

engagement in recesses or sockets in the cooking top unit C for operative association of the splasher back with the cooking top unit.

The combined oven and broiler unit O is interposed between the cooking top unit C and the base unit B adjacent corresponding ends thereof and preferably as illustrated at the left ends thereof. The unit O seats on frame 17 and the supporting member 18 and supports the cooking top unit in fixed vertical relation to the base unit.

With the oven unit O thus disposed between the units C and B, the range is completed by the operative association of the end jacket plates J and the door D.

15 The jacket plates J each include inturned marginal flanges 23 and 24, the latter of which suitably engage the frames 10 and 17 for maintaining the plates in assembled position and the former of which provide a finished appearance to the 20 range.

15 The door D is hingedly connected to the adjacent jacket plate J as indicated at 25 and which door in the assembled range provides access to a compartment defined thereby together with 25 floor 20, the adjacent plate J and oven unit O.

The improved range as thus constructed embodies relatively few simple and light units which are capable of quick assembly and which provide a frameless range which is light in weight and 30 yet sufficiently sturdy to withstand ordinary usage to which gas ranges are subjected.

Furthermore, this construction readily provides for various color combinations by the use of synthetic enamel, particularly on the parts such 35 as the jacket and plates J, door D and the door of the oven unit O which are not subject to extreme heat and the color arrangement can readily be made more attractive by the use of stainless steel and black japan on other parts entering 40 into the range assembly.

40 The combined oven and broiling unit O as is more fully illustrated in Figs. 2, 3 and 5 comprises a box-like portion 27 having a front opening 28 selectively closable by a door 29.

45 The box-like portion 27 is constructed similarly to standard ovens so far as the enclosing walls thereof is concerned, such portion embodying double metallic walls 30 having suitable insulating material 31 therebetween, the construction of 50 the door 29 being substantially the same. The oven compartment further includes an insulated top 32 and a metallic floor 33 in vertically spaced relation to the bottom of walls 30.

55 The door 29 as is more clearly indicated in Fig. 2 bows forwardly to a substantial degree. In other words, the front face of the door is considerably forward of the vertical edges of the door for a purpose which will later appear.

The oven rack 35 and broiler pan 36 are supported by the door 29 as is more clearly indicated in Fig. 5, the oven rack 35 being selectively disposed in vertically arranged guide channels 37 for vertical adjustment of the rack, and the broiler pan 36 being supported by a pair of channels 38 below the series of rack channels 37.

Disposed within the oven compartment or portion 27 is a vertically adjustable base unit or oven floor 39 having a burner 40 on the lower side thereof and preferably integral therewith.

70 As will be seen upon inspection of Fig. 5, the floor 39 and burner 40 when door 29 is closed, rests between the oven rack 35 and the broiler pan 36 and by vertically adjusting the floor 39 and burner 40 the cubic contents of the oven 75 which is practically between floor 39 and the top

of compartment 27 can be varied and the distance between the burner 40 and broiler pan 36 can likewise be varied to suit any desired broiling requirements. The distance of the pastries being baked from the burner 40 can be varied by disposing the oven rack 35 in any one of the vertically spaced pairs of guide channels 37.

By bowing or cupping the door 29 forwardly as disclosed, an oven of comparatively great depth is provided without the necessity of an oven of excessive width and furthermore this formation of the door provides for the seating of a substantial portion of the rack 35 and pan 36 within the door whereby only a portion of each need be withdrawn from the oven compartment 27 upon opening the door.

The door 29 is provided with a transparent panel 41 whereby the position of floor 39 and burner 40 relative to the rack 35 and pan 36 can readily be visualized without the necessity of 20 opening the door 29.

The oven floor 39, and burner 40 are vertically adjustable by means operable exteriorly of the range and in a preferred embodiment thereof comprise the following structure.

Secured within the rear wall of the oven compartment 27 is a channel 41 each of whose opposite legs or walls provides a vertical roller guide channel 42.

Vertically disposed within the compartment 27 adjacent the channel 41 is a sectional mixer tube 43 comprising a lower fixed section 44, and an upper movable section 45 integral with and communicating with the burner 40.

The movable section 45 is provided with rollers 46 disposed within the channels 42 for vertical movement of section 45 with the burner 40 and oven floor 39 and with the adjacent ends of the mixed tube sections 44 and 45 in telescopingly engaged relation as is more clearly indicated in Fig. 3.

Gas is admitted to the sectional mixer tube 43 by the feed line 47 from which the gas will be admitted to the burner 40 irrespective of the vertical adjustment of the burner 40 due to the 45 closely fitting telescopic connection between the mixer tube sections 44 and 45.

Secured to the upper and lower ends of the movable section 45 within the channel 41 are the adjacent ends of a wire cable or other flexible 50 element 48 which extends over pulleys 50 at the top of the oven compartment 27 and pulleys 51 at the bottom of the compartment.

The pulleys 50 and 51 are disposed adjacent the rear wall of the compartment 27 as is more 55 clearly indicated in Figs. 2 and 4 with the pulleys 50 vertically aligned with the pulleys 51. The cable 48 extends through a suitable guide sleeve 52 in the top wall of the oven compartment.

Interposed in the cable 48 is a compensating or 60 counterweight 53 vertically guided in a suitable guide member 54 secured to the oven compartment 27 adjacent a rear corner thereof.

One of the pulleys 50 has its shaft extended in the form of an operating rod 55 to whose free 65 end is secured a handle 56 for rotating the pulley through the rod, the handle being disposed externally of the range R as is indicated in Fig. 1.

The pulleys 50 and 51 may be disposed to either side of the vertical center plane of the oven compartment, when as in the preferred form, they are disposed to the right of such plane the operating handle 56 will be positioned immediately to the left of the door D.

If, however, the pulleys are disposed to the left 75

of such plane the handle 56 will be positioned, as indicated in Fig. 4 wherein rod 55 extends through the hole 55' in the frame 10.

By the provision of the structure disclosed, the oven burner 40 together with the oven floor 39 can readily be vertically adjusted relative to the oven rack 35 and/or the broiler pan 36 by simply turning the handle or keys 56 and the compensating weight 53 is such as to counterbalance the plates 39 and 40 whereby the burner and oven floor will remain in any vertical adjusted position.

With this arrangement of relatively simple parts the cubic contents of the baking oven as well as the distance of the burner 40 from the broiling pan 36 can readily be varied and by the provision of the transparent panel 41 in the oven door the position of the burner can readily be ascertained.

If desired, a suitable scale may be provided at the base of handle 56 and the parts 50 calibrated that the exact position of the oven burner may be readily ascertained.

It is to be noted that the plate or oven floor 39 is spaced at its margins from the inner walls of the oven compartment.

While the counterweight 53 effectively functions to counterbalance the oven bottom 39 for maintenance of position in any vertically adjusted position thereof, it is desirable to provide means for preventing vertical movement of the oven floor when additional weight is imposed in opposition to the counterweight 53, as when food is placed on the oven floor. Such means may partake of various forms but preferably comprise a friction clutch associated with the operating rod 55 and the adjacent pulley 50 as is represented in Fig. 7.

As shown in Fig. 7, a cone engaging seat 70 is rigid with the supporting bracket for the adjacent pulley 50 and through which the rod 55 extends.

Suitably fixed to the rod 55 is a cone member 71 having a friction shoe 72 for normally frictionally engaging the seat 70.

Encircling the rod 55 and disposed between the cone member 71 and the adjacent portion of the pulley supporting bracket is a compression spring 73 for forcing the shoe 72 into frictional engagement with the seat 70.

The rod 55 is preferably splined in the pulley 50 for limited reciprocal movement and for imparting rotation to the pulley upon turning the handle 56.

With this construction, the pulley 50 will normally be braked against rotation by the frictional engagement between the cone seat 70 and the shoe 72.

When it is desired to adjust the elevation of the oven floor 39, the rod 55 is pushed inwardly against the action of spring 73 whereby disengaging the shoe 72 from braking engagement with seat 70 and then rotating the rod the required amount. Upon releasing the rod, the spring 73 will immediately force the shoe 72 into braking contact with seat 70 for maintaining the oven floor in its vertically adjusted position.

In Fig. 6 is illustrated a modified arrangement for vertically adjusting the burner 40 together with the base plate or oven floor 39.

As indicated in this figure, the mixer tube sections 44' and 45' are disposed in a vertical compartment 60 at the rear of the oven compartment 27.

The section 44' has its lower end rotatably par-

allel at 61 against axial movement and the feed line 62 has a swivel connection with such lower end.

The section 44' is externally threaded and the section 45' is internally threaded for a relatively short distance from its lower end for engaging the externally threaded section 44', whereby the section 45' will be moved vertically upon rotation of section 44'.

The section 45' adjacent its upper end extends through a slot 60' in the front wall of the compartment 60 and is detachably secured to the burner 40 as is indicated at 63.

The lower end of section 44' is provided integral or otherwise with a pinion 64 in meshing engagement with a pinion 65 on the lower end of a vertical shaft 66 externally of the oven compartment 27.

The upper end of the shaft 66 is rotatably journaled in a bracket 67 and is provided with an operating knob 68 above the bracket.

In the use of this modified construction, the burner 40 and oven base 39 are vertically adjusted by turning the knob 68 whereby pinion 65 is rotated through the shaft 66 and this pinion in turn imparts rotation to pinion 64 as well as the mixer tube section 44'. Upon rotation of section 44' the section 45' is moved vertically, up or down, according to the direction in which the knob 68 is turned.

It will be readily seen from the foregoing disclosure that a gas range is provided in accordance with this invention which is attractive in appearance, light in weight, durable, provides maximum working space and by the provisions of the novel combined oven and broiler compartment having an adjustable burner, the cubic contents of the oven as well as relation between the burner and broiler pan can readily be varied.

While certain specific embodiments only of the invention have been disclosed, such are to be considered as illustrative, and not restrictive, the scope of the invention being defined in the subjoined claims.

What is claimed and desired to be secured by United States Letters Patent is:

1. In a gas range, a combined baking and broiling unit comprising an open front compartment closable by a swinging door, an oven floor plate having a burner disposed beneath same supported for vertical adjustment within said compartment, an oven rack and broiler pan supported by the door for movement into and out of the compartment upon closing and opening the door, the oven rack and broiler pan being respectively above and below the burner in the closed position of the door, and means externally of the compartment for vertically adjusting the oven floor plate and burner.

2. The structure defined in claim 1 wherein said oven rack is adjustably supported by the door.

3. The structure defined in claim 1 wherein said oven floor plate and said burner are integral, and wherein the margin of said oven floor plate is in substantial spaced relation to the inner walls of the compartment.

4. In a gas range, a combined baking and broiling unit comprising a compartment having side, rear, top, and bottom walls, and a door hingedly connected with the front edge of one of the side walls for opening and closing the front of said compartment, an oven rack and a broiler pan supported by the door in vertically spaced relation with the rack above the pan, for movement

- thereof into and out of the compartment upon closing and opening the door, a combined oven floor plate and burner supported for vertical adjustment from said rear wall and with the plate and burner disposed between the oven rack and broiler pan in the closed position of the door, and manually rotatable means exteriorly of the compartment operatively connected with said combined oven floor plate and burner for vertically adjusting same.
5. The structure defined in claim 4 together with a gas supply conduit adjacent said bottom wall, and a sectional mixer tube disposed between said conduit and said burner, the sectional mixer tube comprising an upper section in fixed relation to said burner and a lower section having its upper end telescopically engaged with the lower end of the upper section.
6. A combined oven and broiling compartment comprising side, rear, top and bottom walls, and a swinging door for opening and closing the front of the compartment, an oven rack and broiler pan supported by the door and projecting within the compartment in vertically spaced relation in the closed position of the door, an oven floor plate having a burner there beneath within the compartment between the oven rack and broiler pan, a gas supply conduit adjacent the bottom wall, a sectional mixer tube interconnecting the conduit and burner comprising an upper section fixed
- 10
- 15
- 20
- 25
- 30

to the burner and a lower section telescopingly engaged with the upper section, and means for vertically adjusting the oven floor plate and burner relative to the oven rack and broiler pan with the upper section of the mixer tube telescoping the lower section thereof during such adjustment.

7. The structure defined in claim 6 wherein said means comprises anti-frictional guide means between said oven floor plate and rear wall, rotatable anti-friction guide means on the top and bottom walls, a flexible element having opposite ends thereof connected to said plate and trained over said rotatable anti-friction guide means, a compensating weight interposed in the flexible element, and manually operable means for imparting rotation to said rotatable anti-friction guide means to raise or lower said plate within the compartment.

8. The structure defined in claim 6 wherein said means comprises a screw-thread connection between the upper and lower mixer tube sections, a pinion fixed to the lower section, a second pinion operatively meshing with the first pinion, a shaft supporting the second pinion, and manually operable means for rotating said shaft whereby the upper mixer tube section is raised or lowered between the oven rack and broiling pan within the compartment.
